Primary Examiner—Antoine Duval Davis
(74) Attorney, Agent, or Firm—Wood, Herron & Evans, L.L.P.

(**) Term: **14 Years**

(57) **CLAIM**
The ornamental design for a discharge portion of a liquid filament dispensing valve, as shown and described.

(21) Appl. No.: **29/150,970**

DESCRIPTION

(22) Filed: **Oct. 31, 2001**

FIG. 1 is a bottom perspective view of the discharge portion of a liquid filament dispensing valve;

(51) LOC (7) Cl. **15-09**

FIG. 2 is a front view of FIG. 1;

(52) U.S. Cl. **D15/144.1**

FIG. 3 is a right side view of FIG. 1;

(58) Field of Search D15/144, 144.1,

FIG. 4 is a left side view of FIG. 1;

D15/144.2; 118/302, 313, 323, 697; 222/1,

FIG. 5 is a top view of FIG. 1; and,

146.5, 189, 482, 504; 239/415; 427/286,

FIG. 6 is a bottom view of FIG. 1.

288.2; 901/143

The elements shown in dash-dot lines form no part of the claimed invention, and are instead included to show environmental aspects of the claimed invention.
